CLAIM

The ornamental design for a lidar device, as shown and described.

DESCRIPTION

FIG. 1 is a top perspective view of a lidar device in accordance with the ornamental design;

FIG. 2 is a front view thereof;

FIG. 3 is a rear view thereof;

FIG. 4 is a top view thereof;

FIG. 5 is a left side view thereof; and,

FIG. 6 is a right side view thereof.

The broken lines in the figures show portions of the lidar device that form no part of the claimed design.
